Patented Apr. 3, 1917.

UNITED STATES PATENT OFFICE.

JOHN P. WEIS, OF NYACK, NEW YORK, ASSIGNOR TO LUCIUS N. LITTAUER, OF GLOVERSVILLE, NEW YORK.

TRIMMING MECHANISM FOR SEWING-MACHINES.

1,221,252.

Specification of Letters Patent.

Patented Apr. 3, 1917.

Application filed January 30, 1914. Serial No. 815,370.

To all whom it may concern:

Be it known that I, JOHN P. WEIS, a citizen of the United States, residing at Nyack, in the county of Rockland and State of New York, have invented certain new and useful Improvements in Trimming Mechanism for Sewing-Machines, of which the following is a specification.

This invention relates to trimming mechanism for sewing machines, and is particularly adapted for that class of vibrating needle machines making a zigzag stitch such for instance as is used for attaching the embroidery strips to various articles, as muslin underwear, etc., and is especially adapted for machines sewing medallions to the body of the goods where it is necessary to cut out the cloth underneath the medallion simultaneously with the stitching operation, the object of the invention being to provide an improved trimming mechanism comprising a pair of trimming means, either of which is capable of being thrown into and out of action at the will of the operator, and one of which may be actuated by a foot pedal and the other by hand, whereby a great variety of work may be performed on one machine which has heretofore necessitated several separate operations.

In practice it has been usual to stitch the embroidery along the edge by one machine, then stitch the medallions in place by another machine while the trimming of the cloth under the medallions was performed by another operation, usually by hand, whereas in the present improvement all of these various operations may be performed on one machine by simply suspending the cutting action of one trimmer while the other is in use.

In the present improvement two trimming mechanisms are provided, both located normally below the cloth plate, but one of which is located in front of the stitching mechanism while the other is in the rear thereof. The front trimming mechanism is effective to trim the edge or edges of the work before it reaches the needle, this trimming mechanism being capable of performing all ordinary work, such as crossing seams, plaits, folds, ruffles, etc., and is so

operative as to enable the material to present a smooth cut edge to the stitching mechanism, so that a piece of embroidery or top strip may be laid upon this cut edge of the body material and then stitched in such manner that the top and bottom edges of the embroidery or strip and the material to which it is attached, may be covered.

The rear trimming mechanism is effective for cutting a bottom ply of material, while another ply is being stitched thereto, and in the present improvement a presser foot cooperates with the front trimmer to guide a strip of material so that it will pass over the cutting blade of the front trimmer and be stitched to the piece which has been previously trimmed by the front trimmer.

As stated, the front trimmer may be readily thrown into or out of operation and when out of operation the cutting knife will be depressed below the top surface of the cloth plate, in which position medallions or other similar forms of embroidery may be stitched to the body of the material, and then the rear trimming mechanism, during such stitching, brought into action by the operator so as to cut out the bottom material from underneath the medallion or embroidery, thus producing an open effect in the work.

In the present improvement the construction is such that one trimming mechanism is, as stated, located in front of the needle to cut in a line somewhat to the right of the needle so that the stitching will cover the cut edge, while the rear trimming mechanism, which will be brought into action when the cutting action of the front trimmer is suspended, for trimming in irregular shapes, is so located that it will cut on a line outside of the needle punctures so that the stitch will have a bite in the fabric on both sides of the stitched lines, so as to make a strong seam.

From the foregoing, it will thus be seen that one of the objects of the invention is the provision of trimming means effective to cut irregular shapes or medallions, and that in the present improvement one trimming mechanism operates to cut the edges of the work before it is stitched, while the other

- operates to cut the work after such stitching, that is, after a part thereof is stitched, and as such stitching proceeds and the organization of the trimming mechanism is 5 such that the trimmers are so located relatively to the needle that one is in position to cut closer to the center line of the stitches than the other, and in the present instance the front trimming mechanism cuts inside of 10 the center line of the stitches while the rear trimming mechanism cuts outside of the line of stitches, and this improved organization makes it possible for the first time to perform all of the work on one and the same 15 machine.

In the drawings accompanying and forming part of this specification, Figure 1 is a right-hand end view, partly in section, of this improved sewing machine; Fig. 2 is a 20 perspective view on an enlarged scale of a part of the mechanism shown in Fig. 1; Fig. 3 represents a piece of work with medallions stitched therein and embroidery along one edge thereof stitched thereto by a zigzag 25 stitch, the upper medallion illustrating how the body material is cut out from under the same; Fig. 4 is a detail plan and side view respectively of a presser foot which may be used when stitching in irregular shaped 30 pieces, such as medallions; Fig. 5 is a perspective view of a presser foot used when stitching embroidery strips along the edges of the work; and Fig. 6 is a detail view of 35 the cutter blade of the rear trimming mechanism particularly adapted for use when sewing medallions.

The front trimming mechanism shown herein is similar to that shown and described 40 in my Patent No. 1,025,552, dated May 7th, 1912, to which reference may be had for a detailed description thereof. Therefore a brief description thereof is only necessary herein.

1 illustrates the bed plate of a sewing machine frame on which is journaled the main shaft 2. The cloth plate 3 is provided with the usual throat plate 4 having the necessary slots for operation of the feed dogs 5, to 45 which feed dogs is connected the feed bar 6 which in turn is connected with the feed rocker frame 7, which rocker frame is, by means of an arm 8, connected with the usual adjustable crank and feed lift eccentric so that the feed has the usual four motion imparted thereto. The needle bar 9 carries the usual thread carrying needle 10, and the presser bar 11 is provided with the usual presser foot shank 12 having the presser foot 13 secured thereto. The front trimming bracket 14 is provided with a guide-plate 15 which is attached thereto for adjusting the trimmer laterally. The trimmer frame 16 is secured in position in the manner shown in the patent hereinbefore referred to. 50

An oscillating shaft 18 supports the trim-

mer lever, one arm 17 of which extends downward while the other arm 20 thereof carries the cutting knife 21 which is secured to the arm at 22. Regulation of the pressure of the trimmer knife is obtained by 50 means of a screw bushing 19. A stationary knife 23 is provided, held in position by a clamping lever 24 having a handle 25 for the purpose of manipulating the stationary knife when it is desired to remove the same, 75 and this knife is held in a recess of that part 26 of the trimmer frame 16. A latch 27 is pivotally secured to the trimmer lever at 28 and co-acts with a pin 29 carried by the adjustable collar 30 carried by the telescopic 80 tube 31, the opposite end of which is provided with a strap 32 encircling the eccentric 33 on the driving shaft. This latch 27 and pin 29 provide a coupling device by means of which the knife 21 may be thrown 85 into or out of operation and permit, when thrown out of action, the knife 21 to be depressed below the surface of the cloth plate. The telescopic tube 31 is provided with a coil spring 31a. The stitching mechanism is 90 the well known construction used with machines known as the Metropolitan sewing machines, so that a detailed description thereof is not deemed necessary.

As hereinbefore stated, the throat plate 4 95 is provided with the usual feed slots 35 for the operation of the feed dogs 5, and this throat plate is also provided with needle hole slots 36 having a stitch finger or tongue 36' between them, over which the stitches are 100 formed, and a cut out portion is provided at 37 for the front trimmer blades. This throat plate is also slotted at 38 for the reception of a knife 39 of the rear trimmer mechanism and the plate is also drilled for the reception of a pin 40 upon which the knife 39 swings. This slot 38 in the throat plate is just to the right of the needle holes looking from the front of the machine, so as to leave 110 a margin of cloth between the right-hand needle puncture and the line of trim. This knife 39 is provided with a penetrating point 41 and a cutting edge 42 and is also provided with an elongated slot 43 to receive a pin 44 carried by an operating lever 45, 115 which lever is pivotally secured to the feed bar 6 as at 46 by means of a shoulder screw.

The rear portion 47 of the pivoted lever has connected thereto a spring 48 the opposite end of which is connected as at 49 to the feed rocker frame 7. An adjustable plate 50 is provided with an elongated slot and a finger tab thereby to permit the same to be shifted into position to limit the movement of the lever 47, this plate sliding on the rocker frame and being clamped in position by a screw 51. Secured to the rear end of the pivoted lever 47 is a rod 52 and this rod projects through the table as at 54 and is connected by means of a swivel 55 with a 120 125 130

lever 56 pivoted to a bracket 57, the opposite end of which lever is connected by a suitable flexible connection, as for instance a chain 59 with a suitable floor treadle so that as the treadle is depressed the rod 52 will be forced upward and thus carry the rear portion of the lever 47 into position into contact with the hub 61 of the rocker frame 7, so that the knife will be depressed. As soon as pressure is removed from the treadle the spring 48 will return the parts to their normal working position with the rear end of the lever 47 resting upon the adjustable plate 50.

From the foregoing it will be seen that the knife actuating lever 47 is secured to the feed bar in such manner that it has the same movement as the feed bar and that by reason of the pin and slot connection 43, 44 between the knife 39 and the lever 47 a lifting motion is given to the front end of the knife so that the knife is swung upon its pivot 40 and thus has the same lifting motion as the feed dog. This knife 39 is made of very thin steel and the cutting edge thereof cooperates with the right-hand edge of the slot 38 thus forming a shear cutting action between the two. The lever 47 is at all times held against the adjustable plate 50 when the treadle is not depressed and should it be desired to do a class of work that does not require this rear trimming mechanism the plate may be so adjusted as to hold the lever 47 up against the hub 61 so that the cutting blade 39 is depressed below the surface of the throat plate, thus rendering it inactive.

In Fig. 4 is shown a presser foot particularly adapted for use when medallions are to be sewed to the work, and this foot is provided with needle holes 62, a stitching finger 63 and a cut out portion 64 for guiding the medallions. This foot is formed with a short turned up end 65 so that the fingers of the operator may manipulate the work very close to the stitching position. In practice, when a piece of work having a square insertion or medallion is being stitched the foot may have to be lifted slightly so that the work can be turned, but on oval or round pieces the bearing of the foot is such as to permit free turning of the work without lifting the foot from the feed, and for this reason the medallion foot is small, covering but very little of the feed surface.

In Fig. 5 is shown a presser foot particularly adapted for use with embroidery work, and this foot has an extended portion 66 provided with a guard 67 adjacent to the knife 21 of the front trimming mechanism and has secured thereto at the front of the foot a U-shaped inclined guide 68 for convenience in guiding the edges of the work.

In Fig. 3 a piece of embroidery or edging

is shown at 69 stitched to the work by means of a zig-zag stitch 71, and a medallion 72 is also shown stitched to the work at the edges thereof by stitches 73, such medallion being shown cut out as at 70.

It will be understood that the various details may be more or less modified without departing from the spirit or scope of the present improvement, and that by means of the present improvement having the front 75 and rear trimming mechanisms organized in the manner shown, in which one or the other may be operated as occasion may require, various kinds of work can be performed on one and the same machine which have 80 heretofore necessitated different operations on different machines, and from the foregoing it will be observed that either of the trimming mechanisms may be thrown into or out of action without interfering with 85 the stitching mechanism.

It will also be understood that in some instances where the article of wearing apparel requires it, an edge of the medallion and an adjoining edge of the edging or embroidery 90 may be connected with the goods by the same stitches, thus also saving one stitching operation, especially where the medallion is of a form that will permit this, as for instance, of considerable length or rectangular, both 95 trimmers operating at the same time to cut in the manner hereinbefore described. In these instances, if the medallion extends to the left of the needles during this operation, both the medallion and the goods 100 would be fed under the presser foot; if however, the medallion extends to the right of the needles, it would be fed over the front of the presser foot and then after the edge in juxtaposition to the edging is sewed the 105 medallion would be laid over on the body of the goods.

I claim as my invention:

1. In a sewing machine for forming medallions, the combination of stitching mechanism for stitching together a plurality of plies of material, and a cutter located in proximity to the needle for cutting out only a portion of the under ply of material, whereby the upper ply will cover or fill in 110 the cut out portion and form a medallion or insertion, the stitching mechanism and cutter being so arranged that the latter cuts the work previously stitched as the stitching operation proceeds.

2. In a sewing machine, the combination of stitching mechanism for stitching together a plurality of plies of material, and a cutter located in proximity to the needle for cutting out only a portion of the under 115 ply of material subsequent to the stitching thereof whereby the upper ply will cover or fill in the cut out portion and form a medallion or insertion.

3. In a sewing machine, the combination 130

- of stitching mechanism including a needle for stitching together a plurality of plies of material, and a cutter located in the rear of the needle for cutting out only a portion of the under ply of material whereby the upper 50 ply will cover or fill in the cut out portion and form a medallion or insertion.
4. In a sewing machine for forming medallions, the combination of stitching mechanism for stitching together a plurality of plies of material, and a cutter located in proximity to the needle for cutting out only from the body portion of the under ply of material to form an endless edge, whereby the upper 70 ply will cover or fill in the cut out portion and form a medallion or insertion, the stitching mechanism and cutter being so arranged that the latter cuts the work previously stitched as the stitching operation proceeds.
5. In a sewing machine for forming medallions, the combination of stitching mechanism for stitching together a plurality of plies of material, a cutter located in proximity to the needle for cutting out only a portion of the under ply of material, whereby the upper 80 ply will cover or fill in the cut out portion and form a medallion or insertion, the stitching mechanism and cutter being so arranged that the latter cuts the work previously stitched as the stitching operation proceeds, 85 said trimming means connected to the feeding mechanism for movement therewith, means for throwing said trimming means into or out of action, and means for limiting the movement of said trimming means.
6. In a sewing machine for forming medallions and having feeding mechanism, the combination of stitching mechanism for stitching together a plurality of plies of material, a cutter located in proximity to the needle for cutting out only a portion of the under 90 ply of material, whereby the upper ply will cover or fill in the cut out portion and form a medallion or insertion, the stitching mechanism and cutter being so arranged that the latter cuts the work previously stitched as the stitching operation proceeds, means for automatically actuating said trimming means, and means for throwing it into and out of operation.
7. In a sewing machine, the combination of stitching mechanism including a needle for stitching together a plurality of plies of material, a cutter located in the rear of the needle for cutting out only a portion of the under 95 ply of material whereby the upper ply will cover or fill in the cut out portion and form a medallion or insertion, means for automatically actuating said trimming means, and means for throwing it into and out of operation.
8. In a sewing machine, the combination of stitching mechanism including a needle for stitching together a plurality of plies of material, a cutter located in the rear of and

to one side of the needle for cutting out only from the body portion of the under ply of material to form an endless edge, whereby the upper 75 ply will cover or fill in the cut out portion and form a medallion or insertion, means for automatically actuating said trimming means, and means for throwing it into and out of operation.

9. In a sewing machine for forming medallions and having feeding mechanism, the 80 combination of stitching mechanism for stitching together a plurality of plies of material, a cutter located in proximity to the needle for cutting out only a portion of the under 85 ply of material, whereby the upper ply will cover or fill in the cut out portion and form a medallion or insertion, the stitching mechanism and cutter being so arranged that the latter cuts the work previously stitched as the stitching operation proceeds, 90 said trimming means connected to the feeding mechanism for movement therewith, means for throwing said trimming means into or out of action, and means for limiting the movement of said trimming means.

10. In a sewing machine for forming medallions, the combination of stitching mechanism for stitching together a plurality of plies of material, a cutter located in proximity to the needle for cutting out only a portion of the under 95 ply of material, whereby the upper ply will cover or fill in the cut out portion and form a medallion or insertion, the stitching mechanism and cutter being so arranged that the latter cuts the work 100 previously stitched as the stitching operation proceeds, means for automatically actuating said trimming means, and pedally operative means for throwing it into and out of operation.

11. In a sewing machine for forming medallions, the combination of stitching mechanism for stitching together a plurality of plies of material, a cutter located in proximity to the needle for cutting out only a portion of the under 110 ply of material, whereby the upper ply will cover or fill in the cut out portion and form a medallion or insertion, the stitching mechanism and cutter being so arranged that the latter cuts the work 115 previously stitched as the stitching operation proceeds, means for automatically actuating said trimming means, and means for throwing said cutter below the surface of the cloth-plate.

12. In a sewing machine for forming medallions, the combination of stitching mechanism for stitching together a plurality of plies of material, operating mechanism therefor, trimming mechanism including a 120 cutter located in proximity to the needle for cutting out only a portion of the under 125 ply of material, whereby the upper ply will cover or fill in the cut out portion and form a medallion or insertion, the stitching mech- 130

- anism and cutter being so arranged that the latter cuts the work previously stitched as the stitching operation proceeds, means for throwing said trimming means into and out of operation, and means carried by said operating mechanism for maintaining said trimming means in or out of action.
13. In a sewing machine for forming medallions, the combination of stitching mechanism for stitching together a plurality of plies of material, a presser foot mechanism under the presser foot of which one ply of material passes and over which and guided thereby another ply of material passes, and automatically operative trimming mechanism including a cutter located in proximity to the needle for cutting out only a portion of that ply of material which passes under the presser foot, whereby the upper ply will cover or fill in the cut out portion and form a medallion or insertion.
14. In a sewing machine for forming medallions, the combination of stitching mechanism for stitching together a plurality of plies of material, a presser foot mechanism under the presser foot of which one ply of material passes and over which and guided thereby another ply of material passes, automatically operative trimming mechanism including a cutter located at the rear of the needle for cutting out only a portion of that ply of material which passes under the presser foot, whereby the upper ply will cover or fill in the cut out portion and form a medallion or insertion, the stitching mechanism and cutter being so arranged that the latter cuts the work previously stitched as the stitching operation proceeds, and means under the control of the operator for throwing said cutter into and out of operation.
15. In a sewing machine having a cloth plate and feeding mechanism, the combination of stitching mechanism including a needle for stitching together a plurality of plies of material, trimming mechanism connected with said feeding mechanism for movement therewith and including a shiftable knife operative in the rear of the needle to cut out only a portion of the under ply of material subsequent to the stitching thereof, whereby the upper ply will cover or fill in the cut out portion and form a medallion or insertion, means for throwing said trimming mechanism into or out of action, and adjustable mechanism carried by the feeding mechanism for adjusting the amount of movement of said feeding mechanism and also effective to maintain said shiftable knife below the upper surface of the cloth plate.
16. In a sewing machine for forming medallions, the combination of stitching mechanism for stitching together a plurality of plies of material, and a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, whereby the upper ply will cover or fill in the cut out portion and form a medallion or insertion.
17. In a sewing machine for forming medallions, the combination of stitching mechanism for stitching together a plurality of plies of material, a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, whereby the upper ply will cover or fill in the cut out portion and form a medallion or insertion, one of said trimming mechanisms effective to cut the edges of the work prior to its being stitched and the other operative to cut the lower ply of material subsequent to the stitching thereof, and means for automatically operating both of said trimming mechanisms.
18. In a sewing machine for forming medallions, the combination of stitching mechanism for stitching together a plurality of plies of material, and a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, and one located in the rear of the other, whereby the upper ply will cover or fill in the cut out portion and form a medallion or insertion.
19. In a sewing machine for forming medallions, the combination of stitching mechanism for stitching together a plurality of plies of material, a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, and one located in front of the needle and the other to the rear thereof, and means for throwing either of said trimming mechanisms into and out of operation at the will of the operator.
20. In a sewing machine for forming medallions, the combination of stitching mech-

- anism for stitching together a plurality of plies of material, a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, and a presser foot mechanism co-operating with said stitching mechanism and with both of said trimming mechanisms and effective to feed one ply of material under the presser foot thereof and to feed and guide another ply of material forming the medallion over the presser foot thereof.
21. In a sewing machine for forming medallions, the combination of stitching mechanism for stitching together a plurality of plies of material, a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, a presser foot mechanism co-operating with said stitching mechanism and with both of said trimming mechanisms and effective to feed one ply of material under the presser foot thereof and to feed and guide another ply of material forming the medallion over the presser foot thereof, means for automatically operating said trimming mechanisms, and means for throwing either of said trimming mechanisms into or out of operation at the will of the operator.
22. In a sewing machine for forming medallions, the combination of stitching mechanism for stitching together a plurality of plies of material, a pair of trimming mechanisms coöperating with the same stitching mechanism, one in position to cut closer to the center line of the stitches than the other, whereby one cuts the edge of the material inside of the center line of the stitches and the other cuts only the lower ply of material outside of the stitches, whereby the upper ply will cover or fill in the cut out portion and form a medallion or insertion, and means for automatically actuating said trimming mechanisms.
23. In a sewing machine for forming medallions, the combination of stitching mechanism for stitching together a plurality of plies of material, a pair of trimming mechanisms coöperating with the same stitching mechanism, one in position to cut closer to the center line of the stitches than the other, whereby one cuts the edge of the material inside of the center line of the stitches and

the other cuts only the lower ply of material outside of the stitches, whereby the upper ply will cover or fill in the cut out portion and form a medallion or insertion, means for automatically actuating said trimming mechanisms, and means for throwing said trimming mechanisms into and out of action.

24. In a sewing machine for forming medallions, the combination of stitching mechanism for stitching together a plurality of plies of material, a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, whereby the upper ply will cover or fill in the cut out portion and form a medallion or insertion, means for automatically actuating said trimming mechanisms, and independent means for throwing each of said trimming mechanisms into and out of action at the will of the operator.

25. In a sewing machine for forming medallions, the combination of stitching mechanism for stitching together a plurality of plies of material, a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, whereby the upper ply will cover or fill in the cut out portion and form a medallion or insertion, means for automatically actuating said trimming mechanisms, and independent means for throwing each of said trimming mechanisms into and out of action at the will of the operator, one of said last means comprising a manually operative means and the other a pedally operative means.

26. In a sewing machine for forming medallions and having driving mechanism and feeding mechanism, the combination of stitching mechanism for stitching together a plurality of plies of material, and a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, whereby the upper ply will cover or fill in the cut out portion and form a medallion or insertion, one of

said trimming mechanisms connected with the driving mechanism and the other with the feeding mechanism.

27. In a sewing machine for forming medallions and having driving mechanism and feeding mechanism, the combination of stitching mechanism for stitching together a plurality of plies of material, a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, whereby the upper ply will cover or fill in the cut out portion and form a medallion or insertion, one of said trimming mechanisms connected with the driving mechanism and the other with the feeding mechanism and one located to operate in the rear of the other, and means for independently throwing said trimming mechanisms into and out of action.

28. In a sewing machine for forming medallions and having a cloth-plate, the combination of stitching mechanism for stitching together a plurality of plies of material, a pair of trimming mechanisms coöperating with the same stitching mechanism, one in position to cut closer to the center line of the stitches than the other, whereby one cuts the edge of the material inside of the center line of the stitches and the other cuts only the lower ply of material outside of the stitches, whereby the upper ply will cover or fill in the cut out portion and form a medallion or insertion, each of said trimming mechanisms including a shiftable trimmer blade, means for automatically actuating said blades, and means for shifting said blades below the upper surface of the cloth-plate.

29. In a sewing machine for forming medallions and having driving mechanism and feeding mechanism, the combination of stitching mechanism for stitching together a plurality of plies of material, a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, whereby the upper ply will cover or fill in the cut out portion and form a medallion or insertion, the inside trimming mechanism having connection with the driving mechanism and the outside trimming mechanism having connection with the feeding mechanism, and means for independently throwing each of

said trimming mechanisms into and out of action.

30. In a sewing machine for forming medallions, the combination of stitching mechanism for stitching together a plurality of plies of material, a pair of trimming mechanisms coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, whereby the upper ply will cover or fill in the cut out portion and form a medallion or insertion, means for throwing said trimming mechanisms into and out of action, and adjustable means for maintaining one of said trimming mechanisms out of action.

31. In a sewing machine for forming medallions, the combination of stitching mechanism for stitching together a plurality of plies of material, a pair of trimming mechanisms coöperating with the same stitching mechanism, and located one in the rear of the other, both of the trimmers being located at the same side of the needle but one in position to cut closer to the center line of the stitches than the other whereby one cuts the edge of the material inside of the center line of the stitches and the other cuts only the lower ply of material outside of the stitches, whereby the upper ply will cover or fill in the cut out portion and form a medallion or insertion, means for throwing said trimming mechanisms into and out of action, and adjustable means for maintaining the rear trimming mechanism out of action.

32. In a sewing machine for forming medallions and having driving mechanism, feeding mechanism and a cloth-plate, the combination of stitching mechanism, a pair of trimming mechanisms both coöperating with the same stitching mechanism, both of the trimmers being located at the same side of the needle but one in position to cut closer to the center line of the stitches than the other whereby one cuts the edge of the material inside of the center line of the stitches and the other cuts only the lower ply of material outside of the stitches, the first effective to cut the edges of the work before it is stitched and the other effective to cut from the body of the work after it is stitched and as the stitching operation proceeds and one having connection with the driving mechanism and the other with the feeding mechanism, and means for throwing each of said trimming mechanisms out of action and maintaining it below the upper surface of the cloth-plate.

33. In a sewing machine having needle

mechanism, feeding mechanisms and a throat-plate provided with a slot, the combination of trimming mechanism including a pivotally supported shiftable knife working in said slot, means connecting said knife with the feeding mechanism, means for throwing said knife into and out of action, means carried by the feeding mechanism for adjusting the throw of said knife and also 5 effective to maintain said knife below the upper surface of the throat-plate, another trimming mechanism located in front of said first trimming mechanism and in front of the needle, and means for automatically 10 operating the same, both of the trimmers being located at the same side of the needle but one in position to cut closer to the center line of the stitches than the other whereby one cuts the edge of the material inside 15 of the center line of the stitches and the other cuts only the lower ply of material 20 outside of the stitches.

34. In a sewing machine having needle mechanism, feeding mechanism and a throat-plate provided with a slot, the combination of trimming mechanism including a pivotally supported shiftable knife working in said slot, means connecting said knife with the feeding mechanism, means for throwing said knife into and out of action, means carried by the feeding mechanism for 25 adjusting the throw of said knife and also effective to maintain said knife below the upper surface of the throat-plate, another trimming mechanism located in front and to one side of said first trimming mechanism and in front of the needle, means for automatically 30 operating the same, and means for throwing the same into and out of action, both of the trimmers being located at the same side of the needle but one in position to cut closer to the center line of the stitches than the other whereby one cuts the edge of the material inside of the center line of the 35 stitches and the other cuts only the lower ply of material outside of the stitches.

35. In a sewing machine for forming medallions and having needle mechanism, the combination of a pair of trimming mechanisms located to operate one in front of the needle and the other in the rear thereof, both of the trimmers being located at the same side of the needle but one in position to cut closer to the center line of the stitches than the other whereby one cuts the edge of the material inside of the center line of the 50 stitches and the other cuts only the lower ply of material outside of the stitches, means for automatically actuating said trimming mechanisms, and a presser foot co-operating with both of said trimming mechanisms, one ply of material passing beneath the same and the medallion above the same.

36. In a sewing machine having feeding 55 mechanism and a cloth plate, the combina-

tion of trimming mechanism having a single pivotal connection with said feeding mechanism for movement therewith and including a shiftable knife, means for throwing said trimming mechanism into or out of action with the shiftable knife below the upper surface of the cloth plate, and slidable means for maintaining said trimming mechanism out of action.

37. In a sewing machine having feeding 75 mechanism and a cloth plate, the combination of trimming mechanism having a single pivotal connection with said feeding mechanism for movement therewith and including a shiftable knife, means for throwing said trimming mechanism into or out of action 80 with the shiftable knife below the upper surface of the cloth plate, and slidable means for maintaining said trimming mechanism out of action, said adjustable means being 85 carried by the feeding mechanism.

38. In a sewing machine having needle mechanism, feeding mechanism and a throat plate provided with a slot, the combination of trimming mechanism including a pivotally supported shiftable knife working in said slot, a single pivotal connection between said knife and the feeding mechanism, means for throwing said knife into and out of action, and slidable means carried by 90 the feeding mechanism for adjusting the throw of said knife and also effective to maintain said knife below the upper surface of the throat plate.

39. In a sewing machine for forming medallions and having driving mechanism, feeding mechanism, needle mechanism and a cloth-plate, the combination of a pair of trimming mechanisms located one to operate in front of the needle and the other in the 100 rear thereof, both of the trimmers being located at the same side of the needle but one in position to cut closer to the center line of the stitches than the other whereby one 105 cuts the edge of the material inside of the center line of the stitches and the other cuts only the lower ply of material outside of the stitches, said front trimming mechanism having connection with the driving mechanism and said rear trimming mechanism having connection with the feeding mechanism, means for independently throwing either of said trimming mechanisms out of operation and below the upper surface 110 of the cloth-plate, and a presser foot co-operating with both of said trimming mechanisms, one ply of material passing beneath the presser foot and the medallion above the presser foot.

40. In a sewing machine having feeding 115 mechanism and needle mechanism, the combination of a throat plate having a slot therein, trimming mechanism having a pivotally supported shiftable knife located in said slot to operate in the rear of the needle, 120

130

said knife having connection with the feeding mechanism for movement thereby, sliding means carried by the feeding mechanism for adjusting the position of the knife 5 and for maintaining said knife below the upper surface of the throat plate, and pedal-ally operative means connected with said knife for throwing it into or out of action.

41. In a sewing machine having feeding 10 mechanism including a rocking member, and needle mechanism, the combination of a throat plate having a slot one edge thereof forming a fixed knife, a pivotally supported shiftable knife located in said slot and oper-

ative in the rear of the needle, a lever hav- 15 ing a pin and slot connection with the knife below the throat plate and pivotally connected with said feeding mechanism in the rear of said knife, means for operating said lever thereby to throw the knife into and 20 out of action, and adjustable means carried by said rocking member for adjusting the throw of said knife and for also maintaining said knife out of action.

JOHN P. WEIS.
